ELECTRIC VIBRATOR MOTOR

W Arthur Ernst, Racine, Wis.

Application May 22, 1958, Serial No. 51,016

Term of patent 14 years

(Cl. D26—5)

Fig. 1 is a top view of an electric vibrator motor showing my new design;

Fig. 2 is a front elevational view thereof; and

Fig. 3 is an elevational view looking at the left-hand end of Fig. 2, the opposite end being the same.

I claim:

The ornamental design for an electric vibrator motor, substantially as shown.
